FIG. 1 is a top plan view of an automobile floor mat embodying my new design;

FIG. 2 is an elevational view thereof as viewed from the lower end of FIG. 1;

FIG. 3 is an elevational view thereof as viewed from the right side of FIG. 1;

FIG. 4 is a fragmentary vertical sectional view on an enlarged scale taken along line 4-4 of FIG. 1;

FIG. 5 is a fragmentary vertical sectional view on an enlarged scale taken along line 5-5 of FIG. 1;

FIG. 6 is a fragmentary vertical sectional view on an enlarged scale taken along line 6-6 of FIG. 1;

FIG. 7 is a fragmentary vertical sectional view on a greatly enlarged scale taken along line 7-7 of FIG. 1;

FIG. 8 is a fragmentary vertical sectional view on a greatly enlarged scale taken along line 8-8 of FIG. 1;

FIG. 9 is a fragmentary portion of the top plan view on a greatly enlarged scale of the area within the circled region 9 of FIG. 1; and

FIG. 10 is a fragmentary portion of the top plan view on a greatly enlarged scale of the area within the circled region 10 of FIG. 1.

The pattern which is partially shown in FIGS. 1 and 10 for ease of illustration is understood to be continuous throughout the areas indicated. The undisclosed bottom is substantially flat and unornamented.

I claim:

The ornamental design for an automobile floor mat, substantially as shown and described.
